and with sufficient funds to make other and additional
investigations in the several lines of information now
available as possible, and to furnish the Bureau with
such additional information as may be necessary to
enable the Bureau to make a full and accurate
investigation. In this connection, the Bureau
will be advised to make a full and accurate
investigation of the information contained in
UNITED STATES
the following documents, which were furnished to the
Bureau by the FBI Laboratory, Washington, D. C.:

UNITED STATES PATENT OFFICE

MOTION CONVERTER

Irven F. Williams, Midland, Mich.

Application May 3, 1947, Serial No. 745,817

Digitized by srujanika@gmail.com

1

This invention relates to file attachments for milling machines, and more particularly to an attachment for filing die openings, punches, etc. to precision accuracy.

One of the prime objects of the invention is to design a file attachment which can be attached to and operated by a milling machine for filing straight lands on dies and punches, or filing square corners in or on work without danger of over-cutting the corners.

Another object is to provide a filing attachment applicable to a conventional milling machine, and by means of which a predetermined, accurate radius can be filed by clamping the work on a turn-table, with the radius point in the center of said table, and then engaging the file to the work so that the filing operation is accomplished by the same operation as required to operate on conventional mill work.

Another object is to provide a filing attachment from which the file may be removed, and hones substituted for finishing the work.

Another object is to provide a file attachment in which the work can be fed from any direction and the feed regulated to provide smooth, even operation, and smooth, accurate and even finish.

A further object still is to provide a file attachment in which the file can be completely used, the worn sections of the file being broken off, and the remaining unused file section adjusted accordingly, so that the entire length of the file can be used, thus eliminating any waste of the file.

Still a further object is to provide means for imparting a reciprocating motion to the file, and provide means for the easy and quick adjustment thereof.

With the above and other objects in view, the present invention consists in the combination and arrangement of parts, hereinafter more fully described, illustrated in the accompanying drawings, and more particularly pointed out in the appended claim, it being understood that changes may be made in the form, size, proportion, and minor details of construction, without departing from the spirit or sacrificing any of the advantages of the invention.

In the drawings:

Fig. 1 is a fragmentary, front-elevational view showing the file attachment secured to the spindle of a milling machine.

Fig. 2 is a top plan view thereof.

Fig. 3 is an enlarged, fragmentary, front-elevational view showing the file and securing means.

Fig. 4 is a sectional, plan view thereof.

PATENT OFFICE

CL. 74—53) **2**

Fig. 5 is an enlarged, detail view showing the spindle with the cam groove therein.
Fig. 6 is a fragmentary, side-elevational view of the actuating lever.

5 Refer now to the drawings in which I have shown the preferred embodiment of my invention. The numeral 8 indicates the quill of the milling machine (not shown) in which the spindle 9 is mounted and secured in the usual manner, the lower end of said spindle being formed with an enlarged hub section 10 in which a cam groove 11 is provided.

10

The file attachment bracket comprises a body member 12 shaped as clearly shown in Figs. 1 and 15 2 of the drawings, the one end 13 being tubular in shape, and is split as at 14, laterally projecting wings 15 being formed integral with the split ends, and a bolt 16 extends through said wings for rigidly clamping them in set position on the 20 quill of the milling machine.

The outer end of the bracket body 12 is offset as at 17, and vertically disposed dovetails 18 are formed as shown and form a slide S in which a file holder 19 is mounted, a slotted opening 20 being provided in the offset section and for a purpose to be presently described.

The file holder 19 is mounted for reciprocal movement in said slide, the edges being angled as at 21 to slidably engage the dovetails 18, and a gib 22 is mounted in facial contact with one of the dovetails, said gib being held in position by means of setscrews 23 or the like.

A cover plate 24 is secured to the face of the holder 19 by means of screws 25, and a plurality of setscrews 26 are mounted in said cover and serve to secure the file F which is mounted in the holder, similar longitudinally disposed screws 27 being provided in the one edge of the holder as shown, to secure the file against lateral movement, these screws 26 and 27 serving to hold the file rigidly in position.

The holder 19 is mounted for reciprocatory movement on the bracket, and is actuated by means of a lever 28 having a cam roller 29 journaled on a pin 30 provided in the one end of the lever, this lever being pivotally mounted on the bracket 12 by means of the setscrew 31, and another setscrew 32 extends through a slotted opening 33 provided in the end of the lever 28, said screw extending through the opening 20 in the back of the offset section 17 and being threaded into the file holder 19, and it will therefore be obvious that as the spindle 9 is rotated, the cam roller 29 will follow the cam path 11, 55 rock the lever 28 on the bolt 31, and impart a

reciprocating motion to the holder 19 in which the file is mounted.

The stroke is governed by the cam groove or path, and when the projecting work-engaging end of the file becomes worn, it is broken off and the screws 26 and 27 are then manipulated to permit lowering of a new unused section of the file into the work-engaging zone, and the file can be easily removed from the work by merely raising the quill of the mill or by lowering 10 the table (not shown).

I wish to direct particular attention to the fact that the holder forms a relatively long bearing so that there is no file bending or deflection, as it engages the work, thus insuring accurate precision finish.

From the foregoing description, it will be obvious that I have perfected a very simple, practical and efficient file attachment which can be readily mounted, and by means of which the entire 20 file can be utilized.

What I claim is:

An attachment for a milling machine having a cylindrical quill, a spindle mounted in said quill and provided with a cam groove therein, 25 comprising a rigid bracket clamped to the quill and having a vertically disposed slide in the outer end thereof, a vertically reciprocable holder

mounted in said slide, a horizontally disposed lever mounted on said bracket at a point intermediate its length, a horizontally extending, slotted opening in the outer end of the lever, a vertically extending, slotted opening in said bracket, a bolt mounted in the slide and projecting through said slotted openings in the lever and bracket respectively, and a roller mounted on the opposite end of the lever and engaging in said cam groove for imparting reciprocating, vertical movement to said holder when the spindle is rotated.
